BAG HOLDER

John H. Rourke, St. Vital, Manitoba, Canada

Application July 7, 1932, Serial No. 621,175
In Canada April 9, 1932

5 Claims. (Cl. 83—26)

The invention relates to improvements in bag holders and an object of the invention is to provide a device which will receive and hold the bag with the mouth thereof fully open to permit of the easy filling of the bag and which is arranged so that the empty bag can be easily and quickly put in place and the filled bag easily removed and which is designed so that it can be readily adjusted to accommodate bags having various sized mouths and bags of various lengths.

A further object is to provide a bag holder having suitably positioned stationary and movable jaws adapted to grip the mouth of the bag and hold it open and to arrange the movable jaws so that they can all be simultaneously opened by the manipulation of foot actuated means in the nature of a double foot pedal provided.

A further object of the invention is to provide a frame having one side thereof so that it can be adjusted towards and away from the other side of the frame, the adjustable part of the frame carrying a stationary and movable jaw which in the movement of such part of the frame is adjusted in position in respect to the other jaws and further to provide the frame with pointed legs for engagement with the ground and to hold the device against shifting when in use and also to provide means permitting of the adjustment of the legs.

30 A further object is to construct the double pedal employed so that it accommodates the movement of the adjustable side of the frame.

A still further object of the invention is to support the rear pair of bag gripping jaws so that they can swing ahead against the pressure of a spring provided, such feature allowing the device to hold bags having a relatively small mouth as well as those with larger mouths.

40 A further object is to construct the stationary and movable jaws so that the mouth of the bag will be positively gripped and such that there is small possibility of the material of the bag being damaged.

45 With the above more important objects in view, the invention consists essentially in the arrangement and construction of parts hereinafter more particularly described, reference being had to the accompanying drawings, in which:—

50 Fig. 1 is a front view of the bag holder.

Fig. 2 is a plan view thereof.

Fig. 3 is a vertical sectional view at 3—3 Figure 1.

55 Fig. 4 is an enlarged detailed horizontal sectional view at 4—4 Figure 1.

Fig. 5 is a horizontal sectional view at 5—5 Figure 1.

In the drawings like characters of reference indicate corresponding parts in the several figures.

The main frame of the bag holder presents the 60 opposing sides 1 and 2 and the back 3 connecting the sides. The side 1 is what I term a stationary side and it is formed from a single piece of bar metal bent to provide a vertical front portion 4 and upper and lower substantially L-shaped 65 arms 5 and 6 extending rearwardly from the front portion and an angle brace 7 extending angularly between the upper and lower arms and having the upper end thereof bent downwardly to the inner side of the portion 4 and securely riveted 70 thereto to reinforce the same.

The side 2 is formed from a single piece of bar metal bent to provide a vertical front portion 8 and two upper and lower rearwardly extending arms 9 and 10, these arms being passed above 75 and below the ends of the arms 5 and 6 and being pivotally connected thereto by a long bolt 11, there being a spacing tube 12 interposed between the ends of the arms 5 and 6. The said side 2 is reinforced by an angle brace 13 similar to that 80 7, the upper end of the angle brace being turned down and riveted to the arm in the same manner as the former brace.

According to this arrangement, it will be seen that if the side 1 of the frame be held stationary, 85 the side 2 can be adjusted towards or away from the same as desired.

A vertical bar 14 is permanently fastened to the back of the frame and the frame, at the front, is supported by similar adjustable legs 90 15 in the form of metal bars having their lower ends pointed. Each leg is supplied with a pair of longitudinally extending slots 16 and 17 and the upper end of the leg is fitted with a laterally disposed eye 18. Two front legs are provided 95 and these are attached to the vertical portions 4 and 8 of the frame, the connection being made by passing a lower bolt 19 through each lower slot of the leg, the bolt being carried by the frame and slidable in the slot and by passing an eye 100 bolt 20 through each upper slot, the eye bolt being carried by the frame and slidably received within the slot. The eye bolt is provided rearwardly in each instance with a winged nut 21 and to the eye of the bolt, I pivotally connect 105 the eccentric head 22 of a lever 23.

According to this arrangement, one can adjust the leg in respect to the frame by turning the lever into a position such that the eccentric head thereof does not jam the leg against move- 110

ment and when a desired adjustment has been made, it is only necessary to swing the lever into a position which will cause the head to effectively jam the leg and hold it in the adjusted position.

5 The rear bar 14 is supplied with a rear leg 24 and this latter leg is attached to and rendered adjustable in respect to the bar in the same manner as the legs previously described.

To each of the eyes 18 of the legs, I connect the 10 upper end of a coiled spring 25 which spring has its lower end suitably fastened to the main frame and these springs operate when the levers 23 are in their released positions to support the weight of the frame and any load carried thereby, from 15 the legs.

To the vertical front portions 4 and 8 of the main frame, I permanently fasten vertically extending similar arms 26 and 27, these arms having their upper ends hooked inwardly to provide 20 opposing stationary jaws 28 and 29. Associated with the stationary jaws, I provide similar movable jaws 30 and 31 which are formed from relatively short lengths of bar iron pivotally attached by pivot bolts 32 to the arms and which 25 have their inner ends curled backwardly on themselves to form the jaw and their outer ends upwardly turned to provide levers. Coiled springs 33 connect the upper ends of the latter levers to the peaks of the stationary jaws, these springs acting to normally maintain the stationary jaws in 30 their closed position which is pressed tightly against the adjacent stationary jaws.

To the lower part of the back of the frame, I 35 permanently fasten a cross bar 34 which has the ends thereof turned forwardly to provide opposing lugs 35 and to these lugs, I pivotally connect the lower ends of a pair of similar vertically extending arms 36 and 37, the said arms being connected together by upper and lower cross braces 40 38 and 39 and having their upper ends terminating in forwardly hooked ends forming stationary jaws 40 and 41 identical to the stationary jaws previously described.

Similar movable jaws 42 are associated with 45 the latter stationary jaws and such movable jaws are identical to those previously described and are held engaged with their associated stationary jaws by coiled springs 43 corresponding to those 33. The rearwardly disposed pair of movable 50 jaws are connected together by an intervening cross bar 44. A coiled spring 45 is provided which has its forward end connected to the upper cross bar 38 and its rear end connected to the vertical bar 14 and the bars 38 and 14 have fastened thereto guide bars 46 and 47, the guide bar 55 46 carrying a bolt 48 which operates in the longitudinal slot 49 supplied in the bar 47.

A double foot pedal is provided for simultaneously opening and subsequently releasing the 60 movable jaws, such foot pedal being arranged so that it can be manipulated by either the left or right foot of the attendant. The foot pedal comprises a somewhat L-shaped rod 50 located at the outer side of the side 1 of the frame and having the bent end rotatably mounted in the lug 35. A stiff bar 51 is located at the outer side of the side 2 of the frame and has the rear end pivotally connected by a vertically disposed pivot bolt 52 to the rear end of the rod. The 65 forward ends of the rod and the bar 51 project forwardly beyond the front portions 4 and 8 of the frame and are guided in their vertical swinging movement by the latter frame portions and by offset guide bars 53 secured to such portions. 70 Chains 54 and 55 connect the rod 50 and the 75 chains 54 and 55 connect the rod 50 and the

bar 51 with the levers of the front movable jaws and chains or similar pulling lines 56 and 57 connect the rod 50 and bar 51 to the cross bar 44 which it will be remembered is attached to the levers of the rear movable jaws.

In the closed position of the jaws, the rod 50 and bar 51 which form the double pedal are in the position shown in the drawings and it will be obvious that if one press down with his foot on the forward end of either the rod or the latter bar, he will simultaneously move the movable jaws to open or released position and obviously upon the foot pressure being relieved, the springs associated with such jaws will immediately close them. It will be also noticed that the arrangement of the parts is such that the side 2 of the frame can be swung towards or away from the side 1 without in any way interfering with the action of the foot pedal.

When it is desired to support a bag by the holder, one will open the jaws by pressing the foot pedal and will then catch the stationary jaws within the open mouth of the bag and then release the foot pedal. The bag is then held suspended by the holder with the mouth thereof open which facilitates filling the same with produce.

As the side 2 of the frame is adjustable towards or away from that 1 and the rear jaws can be pulled ahead when desired, the device can be 105 used for holding bags having mouths of different size and further than this, one can so position the front jaws so that ample clearance can be given one using say a shovel to fill the bag or in other words, the device can be adjusted at the 110 front to accommodate the shovel being used and in this regard, it is to be remembered that the rear jaws can swing ahead against the pressure of the spring 45 when required.

Where the holder is used to support bags more 115 or less of the same length, the legs will be all set to accommodate the length of the bags and will be then locked in that set position by the levers provided, it being understood that when the holder is so set, the bottom of the bag held 120 thereby and about to be filled, will be just nicely resting on the ground.

In cases, however, where bags of varying length are encountered, one will release the levers 23 so that the weight of the frame, bag and contents 125 is carried by the springs 25. The frame will then drop under the weight of the filling bag and permit the bottom of that bag to rest on the ground. In this way, the frame automatically adjusts 130 itself or settles to accommodate the length of bag being filled.

It will be particularly noted also that the jaws are so shaped that they have virtually no tendency to mutilate or otherwise damage the gripped mouth of the bag.

While I have entered into a detailed description of the various parts, it will be understood that the same might be materially modified without departing from the spirit of the invention as set forth in the appended claims.

What I claim as my invention is:—

1. A bag holder comprising an upstanding frame presenting an open front and opposing sides and having one of the sides pivoted for swinging movement towards or away from the other side, similar elevated opposing bag gripping jaws located at the upper front corners of the frame sides, a pair of rearwardly disposed opposing elevated bag gripping jaws carried by the frame and mounted for simultaneous forward 145 movement, the front jaws being guided in their vertical movement by the frame portions and the rear jaws being guided by offset guide bars secured to the frame and having the rear ends pivotally connected to the frame 150

swinging movement, spring means resisting the latter swinging movement and manually actuated means for simultaneously releasing the grip of the jaws on the sides of the opened mouth of a 5 bag gripped thereby.

2. In a bag holder, an upstanding frame presenting an open front, opposing sides and a back portion connecting the sides, a pair of elevated bag gripping jaws carried by the forward upper 10 corners of the frame sides, a pair of opposing elevated interconnected bag gripping jaws carried by the back portion of the frame and mounted for forward swinging movement in regard to the frame and spring means normally resisting 15 the forward swinging movement of such latter jaws.

3. A bag holder comprising an upright frame presenting an open front, opposing sides and a back portion, the back portion being integrally formed with one of the sides and the other of the sides being pivotally connected to the back portion for swinging movement towards or away from the opposite side, a pair of opposing forward elevated bag gripping jaws carried by the 20 forward upper corners of the frame sides, a pair of rearwardly disposed opposing elevated bag gripping jaws carried by the back portion of the frame and mounted for simultaneous forward swinging movement, spring means resisting the forward swinging movement of the latter jaws and manually operated means for simultaneously releasing the grip of all jaws.

the forward swinging movement of the latter jaws.

4. A bag holder comprising an upright frame presenting an open front, opposing sides and a back portion, the back portion being integrally formed with one of the sides and the other of the sides being pivotally connected to the back portion for swinging movement towards or away from the opposite side, a pair of opposing forward elevated bag gripping jaws carried by the forward upper corners of the frame sides, a pair of rearwardly disposed opposing elevated bag gripping jaws carried by the back portion of the frame and mounted for simultaneous forward swinging movement, spring means resisting the forward swinging movement of the latter jaws and manually operated means for simultaneously releasing the grip of all jaws.

5. In a bag holder, an upstanding frame presenting an open front and opposing sides and having one of the sides pivoted for swinging movement towards or away from the other side, similar elevated opposing bag gripping jaws located at the upper front corners of the frame sides, a pair of rearwardly disposed opposing elevated bag gripping jaws carried by the frame and mounted for simultaneous forward swinging movement and means yieldingly resisting the forward swinging of the latter jaws.
